(57) **CLAIM**

The ornamental design for a food production mat, as shown and described.

DESCRIPTION

The present invention relates to the ornamental design of a mat that may be placed on a floor.

FIG. 1 is a top view of a first embodiment of a section of a food production mat showing our new design;

FIG. 2 is a perspective view thereof;

FIG. 3 is a top view of a second embodiment of a section of a food production mat;

FIG. 4 is a perspective view thereof;

FIG. 5 is a top view of a third embodiment of a section of a food production mat; and,

FIG. 6 is a perspective view thereof.

The broken lines shown in the drawings are for illustrative purposes only and form no part of the claimed design.
